Primary Examiner — Eric Goodman*Assistant Examiner* — Brett Miller(74) *Attorney, Agent, or Firm* — Gregory S. Darley-Emerson; Steven W. Miller**CLAIM**

The container with ornamentation, as shown and described.

DESCRIPTION

FIG. 1 is an isometric view of a container with ornamentation, embodying the new design;

FIG. 2 is a left view thereof;

FIG. 3 is a right view thereof;

FIG. 4 is a front view thereof;

FIG. 5 is a back view thereof;

FIG. 6 is a top view thereof; and,

FIG. 7 is a bottom view thereof.

The broken lines are for the purpose of illustrating portions of the article and boundaries of the claim and form no part of the claimed design.
